UNITED STATES PATENT OFFICE.

ARTHUR J. SWEET, OF WAUWATOSA, WISCONSIN.

STREET-LANTERN.

1,233,617.

Specification of Letters Patent. Patented July 17, 1917.

Application filed May 14, 1915. Serial No. 27,986.

To all whom it may concern:

Be it known that I, ARTHUR J. SWEET, citizen of the United States, residing at Wauwatosa, in the county of Milwaukee and 5 State of Wisconsin, have invented certain new and useful Improvements in Street-Lanterns; and I do hereby declare the following to be a full, clear, and exact description of the invention, such as will enable 10 others skilled in the art to which it appertains to make and use the same.

My invention relates to lighting appliances and more particularly to means for effectively housing and utilizing lighting 15 units for street lighting and other forms of outdoor illumination, although the same be applied also to indoor purposes. For street lighting and the like, it has been proven desirable to distribute the light fairly evenly, 20 which purpose can be attained by housing the lamp in a properly shaped and proportioned prismatic refractor. However, such an inclosing of a lamp retards the free radiation of heat from the latter, so that the 25 resulting temperature may damage the mounting of the lamp or even a part of the glass bulb of the lamp itself. This danger is increased when the lamps or lighting units used have light giving elements run at 30 high temperatures, as is the case with the more efficient of the modern illuminants, such as the gas-filled tungsten lamps. Consequently, it is important that the sockets and other parts associated with the mount- 35 ing of such lamps should be cooled: but this cooling must not extend to the part of the lamp housing the light-giving element, otherwise the efficiency of the light production will be lowered.

40 In using such high-temperature lamps within inclosing globes or lanterns, it has heretofore been customary either to make no special provision for ventilation; or to effect the latter by openings at the top and bottom 45 of the inclosure, thereby creating an upward current of air past the lamp, which current usually diverged outwardly without striking the lamp base at all. In the former case, damage to the socket and even to the upper 50 part of the lamp bulb has often resulted. In the latter case, the cool air first contacts with the active portion of the lamp before passing on to the upper part of the bulb and the lamp mounting: consequently, this air 55 is warmed to such an extent as greatly to lessen its effectiveness for cooling the socket.

and the upper portion of the bulb. Moreover, by expending the greater portion of its cooling effect on the active part of the lamp, the air reduces the temperature and 60 hence the efficiency of the lamp. Consequently, the ventilating methods heretofore in use have decreased the luminous efficiency of the lighting units, or have been utmost ineffective in cooling the parts needing to be 65 cooled, or both.

My invention aims to overcome these difficulties by subjecting the upper portion of the lamp bulb (or other lighting unit) and the mounting for the lamp to strong currents 70 of air, but screening the active portion of the lamp from most, if not all of this circulation of air. It also aims to provide simple and positive means for adjusting the refracting inclosure with respect to the lamp, so 75 as to secure the desired distribution of light from the latter: or, where both a refractor and a reflector are used, for adjusting the position of the lamp simultaneously with respect to both. It also aims to provide sim- 80 ple means (operated without the use of tools) for lowering the inclosing refractor to give protection from rain or snow, for keeping insects from entering the hood, for utilizing by reflection the upward rays of light 85 from the lamp, for utilizing any existing wind to create a ventilating current of air through the hood, for maintaining both the lamp and the light distributing elements (i. e. the refractor and the reflector) vertical 90 in spite of a change in position of the supporting element: for insulating the appliance as a whole from its support:—for readily adapting the same appliance to lighting units of distinctly different types 95 or sizes: for shielding the insulation from the weather: for permitting ready access to the reflector for cleaning the latter: and for adjusting the amount of air contacting with the active part of the lamp. Other objects 100 will appear from the following specification and from the accompanying drawings, in which—

Figure 1 is a vertical section through a street lantern embodying my invention. 105

Fig. 2 is a vertical section through the upper part of the same, taken at right angles to Fig. 1.

Fig. 3 is a fragmentary upward view taken from the line 3—3 of Fig. 1. 110

Fig. 4 is a fragmentary plan view of the embodiment of Fig. 1.

Fig. 5 is a fragmentary vertical section through the same embodiment with the lamp removed, the refracting element lowered, and one of the hooks turned to permit a 5 detaching of the refractor.

While my invention may be utilized with substantially equal effectiveness with various illuminants and various types of light-distributing (or refracting and reflecting elements), I have shown it in the drawings as used in connection with a tungsten lamp supported by a lantern or hood hung from a loop 19, the lamp itself being mounted in a socket 14 suitably fastened to the hood or body of the appliance. This body member may be of various shapes and materials, but is here shown as including an arched roof or hood proper 12 having depending sides or flanges 13 and equipped on its interior with 10 a plurality of lugs 9. Threaded into these lugs respectively are the vertical shanks 11 of supporting members having at their lower ends hooks 8. Seated in each of the said hooks 8 is a pin 7 projecting radially from 15 an angle-sectioned ring 6, which ring supports an inclosing globe for housing the lamp and re-directing the light of the latter. This globe or housing is here shown as of the prismatic refracting type, comprising 20 an outer element 2 equipped with a rim seated in the ring 6 and having vertically disposed prismatic faces on its interior, and an inner element 3 equipped with outwardly directed and horizontally disposed prisms. 25 The two elements 2 and 3 are separated by asbestos washers 5 serving as an expansion joint from between the same, and have the lower ends of both closed by a cap 32.

Resting upon the upper edge of the ring 30 6 is a reflector 10, preferably of metal, which reflector has integral therewith a perforated rim 15 extending substantially to the inner surface of the side walls 13 of the body member of the appliance. The pins 7 preferably have inner heads 37 snapping over the upper edge of the refractor member, so that a raising of the latter will carry the ring 6 and the reflector 10 upward with it. By thus raising the ring 6 until the pins 7 clear 35 the tips of the hooks 8 and then slightly rotating the refractor and ring members, the pins 7 may be disengaged from said hooks, thereby permitting the refractor or translucent housing to be lowered for affording 40 access both to the interior of this housing and to the lamp and socket. In this connection, I preferably provide a chain 35 secured at its ends to the ring 6 and the wall 13 of the body member, which chain will support 45 the housing when thus lowered, as shown in Fig. 5.

When the housing is thus out of the way, the hook members may readily be turned in either direction, so as to alter the distance 50 between the hooks 7 and the lugs 9, thereby

changing the relative vertical position of the lamp and the subsequently raised translucent housing, so as to vary the light distribution. The shank 11 of each hook projects through a radial slot 38 in the perforated portion 15 70 of the reflector member, but the hook portions 8 are normally turned at an angle to the said slots and present upwardly directed ends facing the said perforated portion. Upon partially rotating each hook to bring 75 the free end, into alignment with the corresponding slot, as shown in Fig. 5, the reflector member may be dropped out of the body member, thereby affording access to the interior of the latter and to the lamp socket 14 80 mounted therein.

This lamp mounting preferably is also adjustably positioned, so that it may be moved vertically for a distance corresponding to the effective difference in length between 85 different sizes or types of lamps suitable for use in the classes of lighting for which my fixture is specially adapted. For example, in Fig. 2, the socket proper is carried by a pair of metal stirrups 29 projecting horizontally and each is equipped with a return bend portion 30 affording two aligned perforations through which a screw 26 extends, this screw being threaded into a lug 25 depending from the hood 12 and being locked 90 by a nut 28.

Threaded upon each screw 26 and interposed between the perforated parts of each return-bend portion 30 of one of the stirrups is a knurled nut 38, which when turned in 100 either direction will afford a vertical adjustment of the adjacent stirrup and hence of the socket 14. However, the threading on the screw 26 is preferably cut away for a considerable part of its length: so that by 105 turning each nut 38 until it clears the upper portion of the thread, this nut (together with the stirrup carried thereby) may quickly be dropped to the lower part of the thread and screwed upon the latter. By 110 suitably proportioning the length of the unthreaded part of each screw and by equipping the latter with a head 27 affording a stop at the lower end of the lower thread, I enable the socket to be quickly moved from a 115 position corresponding to a relatively long lamp to a distinctly shorter one, the term length being here used as referring to the distance between the lamp base and the effective center of the light giving element. 120

While the annular foraminous element 15 affords a screen for keeping insects out of the interior of the hood, its perforations permit the entrance of air into the latter, thereby allowing currents of air to enter 125 and cool the socket. However, the reflector portion 10 of the same annular element acts as a screen for preventing this cool air from impinging against the portions of the lamp bulb housing the filament. Consequently, the 130

light-giving part of the lamp (which is protected against lateral or upward air currents by the translucent refractor) may be maintained at a relatively high temperature 5 and therefore at high efficiency. To augment the currents of air passing through the hood above the reflector-screen 10, I preferably equip the hood with a chimney construction comprising an inner cylindrical 10 chimney 22 equipped at its upper end with an outwardly and downwardly directed flange 39, and an outer chimney 23 having its lower end about in horizontal alinement with said flange. The outer chimney preferably 15 has its upper end slightly contracted and is supported by stirrups 24 having at their upper ends downward bends which hold the lower chimney without requiring the latter to be otherwise fastened.

20 Housed by the two chimneys, but out of contact with both, is an insulator 21 having a pair of grooves at right angles to each other. Seated in these respective grooves and freely slideable along the latter are a 25 pair of U shaped members 16 and 17, the former of which is a U bolt fastened rigidly to the hood 12. The other member 17 is fast upon the dome or small hood 18 carried by the suspension loop 19, which 30 dome also preferably carries a bumper 20 of insulating material positioned so close to the insulator 21 as to intercept the arched portion of the U bolt 16 in case the latter is raised, thereby preventing this U bolt and 35 the body of the fixture carried by it from being accidentally detached from the said insulator. It will be evident from Fig. 1 that lateral air currents striking the exterior of the hood 12 will be deflected into the 40 space between the two chimneys, thereby creating a current as shown by the arrows 40 and simultaneously creating an upward suction of air through the inner chimney.

45 Thus, any prevailing movements of air will create a forced draft through the hood, tending to ventilate the interior of the hood and to cool the lamp mounting. This draft will be increased somewhat by the connection currents due to the heating of the air 50 around the main portion of the lamp, but as the latter is almost entirely inclosed by the refractor member and the reflector 10, the movement of air within the said inclosure will be comparatively slight and with a 55 high candle-power lamp might not be sufficient to prevent an overheating of the lamp bulb. To avoid such an overheating, I preferably provide means for admitting a limited amount of air through the bottom of 60 the inclosure, as for example by providing threaded openings 33, one or more of which may be closed by screws 34 so as to adjust the amount of air entering through the said openings and passing the main part of the 65 lamp. It will be evident that by varying

the number of openings thus connecting the interior of the glass inclosure with the outer air I can readily vary the proportion of air impinging respectively against the upper and lower parts of the lamp, or against the 70 light-giving part of the lamp and the mounting for the latter.

It will also be evident that the hook members supporting the inclosure and the screws supporting the socket afford two distinct 75 means for adjusting the relative vertical positions of the lamp and the refractor, so that by combining the two I am able to secure the requisite movement without distorting or greatly altering the general appearance 80 of the fixture. In damp weather, the dome 18 and the flange 39 will coöperate to shed rain or snow entering the outer chimney, thereby preventing the same from entering the interior of the body member. Should 85 snow or sleet pack into the outer chimney while the fixture is not in operative service (as in the day-time) this will block the normal draft-creating function of the chimney. Then when the lamp is lighted, the heating 90 of the air within the hood 12 will soon melt the snow or sleet, which latter will run down the exterior of the hood, leaving the chimney elements clear for their normal function. Should the loop 19 be tilted in any direction 95 (as is likely to happen if this loop is suspended from a wire or strand stretched across a street) the weight of the main portion of the fixture will cause the latter to adjust itself to a vertical position by effect- 100 ing a sliding of the U shaped members 16 and 17 on the insulator 21. Consequently, the lamp, together with the refractor and reflector members will automatically be maintained by gravity in precisely vertical positions, thereby affording exactly the light distribution for which the said members were 105 designed. However, I do not wish to be limited to this particular form of an insulating universal joint, nor to the particular type 110 of translucent housing, nor to other of the details herein disclosed, it being evident that the construction might be modified in many ways without departing from the spirit of my invention.

115 I claim as my invention:

1. A lighting appliance including a hood, a lamp, a translucent light-distributer and a substantially flat reflector all carried by the hood: means for moving the lamp with respect to the hood: and independent means for simultaneously moving the light-distributer and the reflector with respect to the hood.

2. A lantern including a hood, a lamp 125 socket, a stem depending from the hood, projections on said stem defining portions spaced by an intermediary part of the stem, a support for the lamp socket freely slideable on said intermediary part of the stem, 130

and means for securing said support to the stem portions having said projections, the spacing between said last-named portions corresponding to the differences in the effective lengths of various sizes or types of lamps fitting the said lamp mounting.

3. A lantern including a hood having an opening at the top, a support for said hood, a roof carried by the support and disposed over the said opening: a chimney carried by the hood and encircling said roof but out of contact with the latter, and a flexible joint connecting the support and the hood and disposed within said chimney below said roof.

4. A lantern including a hood, a support for the same, an insulating member disposed therebetween and equipped with a pair of relatively transverse peripheral grooves, a pair of **U** bolts carried by the hood and support respectively and having their bends seated respectively in the said grooves, and a guard of insulating material interposed between said member and the support for preventing a relative vertical motion of the said **U** bolts.

5. A lantern including a hood, a support for the same, an insulating member disposed therebetween and equipped with a pair of relatively transverse peripheral grooves, a pair of **U** bolts carried by the hood and support respectively and having their bends seated respectively in the said grooves, a guard of insulating material interposed between said member and the support for preventing a relative vertical motion of the said **U** bolts: and a cover carried by the support and roofing over both said members and said guard.

6. A lantern including a hood, a lamp supported thereby: an inner and an outer chimney both mounted on the hood. The inner thereof connected with the interior of the hood and the outer thereof open at both

ends to the outer air: means associated with the hood and the outer chimney for causing a lateral air current to cause an upward draft through the outer chimney, thereby producing an upward suction of air from the interior of the hood through the inner chimney: and means for restricting the access of the said upwardly sucked air substantially to a predetermined part of the lamp.

7. A lantern including a hood, a lamp supported thereby: an inner and an outer chimney both mounted on the hood, the inner thereof connected with the interior of the hood and the outer thereof open at both ends to the outer air: means associated with the hood and the outer chimney for causing a lateral air current to cause an upward draft through the outer chimney, thereby producing an upward suction of air from the interior of the hood through the inner chimney: and means for controlling the relative proportions of the said upwardly sucked air contacting respectively with upper and lower portions of the lamp.

8. A lantern including a hood, a lamp supported thereby: an inner and an outer chimney both mounted on the hood, the inner thereof connected with the interior of the hood: means associated with the hood and the outer chimney for causing a lateral air current to cause an upward draft through the outer chimney, thereby producing an upward suction of air from the interior of the hood through the inner chimney: a light-distributer substantially housing the light-giving portion of the lamp: means for supplying the said upwardly sucked air partly through the light-distributer and partly outwardly of the latter, and means for varying the proportion of the said air supplied through the light-distributer.

ARTHUR J. SWEET.
